175,655

LAMP

Gerald E. Thurston, Cranford, N. J.
Application April 26, 1955, Serial No. 35,675

Term of patent 7 years
(Cl. D48—20)

Fig. 1 is a plan view of a lamp, and
Fig. 2 is a side elevation thereof, showing my new design.

I claim:
The ornamental design for a lamp, substantially as shown.
